231

UNITED STATES PATENT OFFICE.

ARTHUR W. KOINER, OF RICHMOND, VIRGINIA.

SASH-FASTENER.

1,236,451.

Specification of Letters Patent. Patented Aug. 14, 1917.

Application filed April 13, 1916. Serial No. 90,901.

To all whom it may concern:

Be it known that I, ARTHUR W. KOINER, a citizen of the United States, residing at Richmond, in the county of Henrico and State of Virginia, have invented certain new and useful Improvements in Sash-Fasteners, of which the following is a specification.

My invention relates to sash fasteners. The object of my invention is to produce a device adapted to hold a window sash in raised or open position against the force of gravity or against the action of a spring attached thereto to overcome the force of a counter-weight. A further object thereof is to produce a device by which a window sash may be held open and which may be released to permit its closing from a position remote therefrom. Another object thereof is to produce a pivoted bar carried on a window frame adapted to engage a plate on the sash to hold the sash in open position together with means for closing the sash when released from engagement of said locking bar and means for releasing the engagement of the bar with the sash from a remote position; and a still further object of my invention is to produce a more simple, cheap and efficient sash fastener than has heretofore been attained.

To these ends my invention includes the combination and arrangement of component parts to be hereinafter described and more particularly pointed out in the claim.

In the accompanying drawings, in which like reference characters indicate similar parts:

Figure 1 is an elevation of a window frame and sash equipped with my device.

Fig. 2 is a side view of the same in open position; and

Fig. 3 is a similar view thereof in closed position.

Referring to the drawings, 1 indicates a window frame of ordinary construction in which are carried the sash 2 which, as shown, may be supported in adjusted positions by the sash weights 3 in the ordinary way. It will be appreciated however that my device may be applied to window sash that are not supplied with counter-weights or other means for holding same in open positions.

For the purpose of overcoming the action of the counter-weights 3 and drawing the sash to closed position when released, as

hereinafter described, I provide the coil spring 4 having rings 5 and 5' at their opposite ends adapted to engage the hooks 6 and 6' fastened in the sill and lower end of the sash respectively. Said spring is of such strength that when stretched by the opening of the sash it will be capable of drawing the sash closed against the force of the counter-weights 3 when released from engagement with the locking bar 7. It will also be appreciated that said spring may be removed from position when not in use.

The means for holding the sash in open position comprises the bar 7 having an orifice adjacent to its inner end, through which it may be pivotally fulcrumed on a screw 9 secured on the frame 1 at right angles to the plane of the sash 2. The inner end of said bar is bent outwardly from the plane of the window frame and its extremity 10 is preferably rounded to limit the area of contact with the shoulder 12 on the plate 11 carried on the sash, hereinafter described. The opposite end 13 of the bar is provided with an orifice 14 through which a cord 15 may be attached while the opposite end of the cord 15' is placed in a position remote from the window.

Adjacent to the end of the longer member of said bar an eyelet 16 is secured upon the window frame between the sash and the bar and the cord 15 is passed through same intermediate of its ends.

At a pre-determined position on the frame of the window sash and adjacent to the edge of the window frame a plate 11 is attached. Said plate comprises a thickened portion 18 having an orifice therein, through which a screw 19 may be passed to secure same on the sash, and a depending apron 21 of lesser thickness than the main portion of the plate, which forms therewith a shoulder 12 adapted to be engaged by the rounded head 10 of the bar 7 to hold the sash in open position. The outer angle of said shoulder is preferably beveled to limit to the minimum the contacting surfaces of same and the head 10 of the bar to facilitate their disengagement. It will be appreciated that the apron 21 may be dispensed with if desired, but is provided for the purpose of preventing scratching or marring of the sash in the operation of the device.

In operation, the spring 4 may be attached to the hooks 6 and 6' on the sill and the sash respectively, and the sash raised

with one hand to such position that the bar 7 will engage the shoulder on the plate 11 and thus hold the sash in raised position. The free end of the cord 15' may then be carried to a position remote from the window and when it is desired to have the window closed a tug on the cord will operate the bar 7 to disengage its head from contact with the plate 11 and thus permit the sash 10 to be closed by the action of the spring 4. It will be appreciated that such arrangement will permit a person to close a bedroom window from a position remote from the open window.

Having thus described my invention, what I claim as new and desire to secure by Letters Patent is:

A sash holder, comprising a bar pivotally secured on a window frame having an out-

wardly bent upper end provided with a rounded extremity, a plate carried on a window sash having a projecting beveled shoulder thereon, adapted to be engaged by the upper end of said bar to hold the sash in open position, an eyelet secured upon the window frame adjacent to the opposite end of said bar; and a flexible cord attached to the lower end of the bar and passing through said eyelet by which the engagement of the bar and plate may be severed from a position remote from the window.

In testimony whereof I hereby affix my signature in the presence of two witnesses.

ARTHUR W. KOINER.

Witnesses:

J. J. OWEN,
G. W. KOINER.
